(57) **CLAIM**

We claim the ornamental design for an medical device for noninvasive electrical brain stimulation, as shown and described.

DESCRIPTION

FIG. 1 is a top front right perspective view of a medical device for noninvasive electrical brain stimulation;

FIG. 2 is a top rear left perspective view of a medical device for noninvasive electrical brain stimulation;

FIG. 3 is a left side elevational view of a medical device for noninvasive electrical brain stimulation, the right side being a mirror image thereof;

FIG. 4 is a front elevational view of a medical device for noninvasive electrical brain stimulation;

FIG. 5 is a rear elevational view of a medical device for noninvasive electrical brain stimulation;

FIG. 6 is a top plan view of a medical device for noninvasive electrical brain stimulation; and,

FIG. 7 is a bottom plan view of a medical device for noninvasive electrical brain stimulation.

In the drawings, the broken lines depict unclaimed environmental subject matter and form no part of the claim.
